UNITED STATES PATENT OFFICE.

ANDREW THOMA, OF CAMBRIDGE, MASSACHUSETTS, ASSIGNOR TO NORTH AMERICAN CHEMICAL COMPANY, OF NEW YORK, N. Y., A CORPORATION OF MAINE.

SHOE-BOTTOM FILLER AND METHOD OF MAKING THE SAME.

1,032,312.

Specification of Letters Patent.

Patented July 9, 1912.

No Drawing.

Application filed May 11, 1908. Serial No. 432,083.

To all whom it may concern:

Be it known that I, ANDREW THOMA, a citizen of the United States, and resident of Cambridge, in the county of Middlesex and 5 State of Massachusetts, have invented an Improvement in Shoe-Bottom Fillers and Methods of Making the Same, of which the following description is a specification.

My present inventions relate to a shoe-bottom 10 filler and its manufacture, although not restricted thereto, my filler being an improvement on the previous inventions of my Patents Nos. 832,002; 855,868; 861,555. These patents relate to waxy, sticky, cementitious compounds, which when restricted 15 to a shoe-bottom filler, preferably have a granular nature. The granules, as for instance of cork, are coated with a permanently sticky, gummy mass forming a 20 silent, waterproof, compact body when cold, the binding agent being rendered soft and fluid at a low melting heat, and capable of setting quickly when placed in a shoe-bottom, then forming a compact, but re- 25 silent, layer between the innersole and the outersole of a welt shoe. In my present filler, I aim to retain the special advantages 30 of my previous inventions, as to the permanency of the adhesive qualities and the non-oxidizing character of the cementitious material or binder, which remains substantially the same to the end, while at the same time getting rid of certain disadvantages, as particularly the sensitiveness to heat after once 35 set, the tendency to follow the knife or dauber or spatula when being laid, the liability of the waxy or gummy binder to penetrate or be absorbed by the ground cork (or other granular body), etc.

40 My filler invention, broadly stated, consists of a shoe-bottom filler having a waxy-base, combined with a restraining agent of a pasty nature, the proportions being such that the compound is firm under practicable 45 conditions of temperature in use, elastic, and sleek under a smoothing iron or daubing tool when applied to the shoe or leather. In other words, my invention, broadly stated, resides in providing a shoe-bottom 50 filler of the kind explained in my above patents (embracing a comminuted fibrous or granular body united by a waxy or gummy, sticky, heat-sensitive binder) with a stiffen-

ing controller which, when set, is not sensitive to heat, whereby substantially all the 55 advantages of my previous fillers are retained but the tendency thereof to flux or soften unduly in the shoe in the presence of low heat is substantially eliminated. I have found that by combining a paste-making ingredient, preferably one which becomes 60 pasty or mushy when moistened with water and then stiffens when it parts with the water, such as dextrin or flour (or any of the list of such vegetable, animal, or mineral 65 stiffeners hereinafter mentioned), with the sticky waxy binding material (of my patents above) I get various surprising results, as for example the natural tendency of the paste to dry out and become brittle is no 70 longer present, but the compound has the permanent resiliency and stickiness of the waxy or gummy compound, excepting that it is modified in degree, the natural tendency of the paste to keep on drying until brittle and 75 to become soggy and heavy is no longer present, but on the contrary it sets quickly, in accordance with the nature of the quick-setting waxy or gummy compound (as explained in my patents above), the natural 80 sensitiveness to low heat of the waxy compound is no longer present, but, when once set, it has a remarkably firm, tough, and still 85 resilient character, being very much like leather in this respect, and not liable to soften under mild heat as before, the compound when first heated for application to a shoe is subservient to moisture, even to wet steam in the preferred composition, which unites with the pasty component and 90 gives it a sleek, smooth surface which permits the molding knife or tool to slip smoothly over it when pressing it into a shoe bottom, and finally it is softer, and hence more easily crowded and molded into 95 the shoe cavity because of the presence of the pasty ingredient, while on the other hand, when it has finally set it quickly becomes, not only permanently set, but tougher, stronger, and more leather-like than without the pasty ingredient. There are other 100 advantages besides the six principal advantages just mentioned, such as the easy and convenient process of manufacture, the advantageous method of use, the permanency or non-changing character before use 105

of the product in its preferred form (being practically as unchangeable in this respect as the articles of my filler patents above mentioned), etc., but the most important 5 practical advantages are the permanent toughness or non-liability to soften under moderate heat when once heated and set and installed, and the sleek, easy-smoothing character of the compound when being applied under normal conditions. While each 10 of the enumerated advantages is of peculiar value in improving the shoe and aiding the shoe manufacturer and the filler manufacturer, the chief object of the invention is to provide, by admixing a stiffening component 15 with the waxy or gummy granular filler, a controlling force or influence over the subsequent fluxing or tendency to soften of the waxy or gummy filler after it is in 20 the shoe and possibly on the wearer's foot.

A shoe filler possessing in itself a permanent inherent cohesiveness and adhesiveness is of the greatest value, especially when the cementing-agent allows itself to be easily 25 manipulated by the simple use of a low heat, but when once installed in a shoe bottom it is of decided disadvantage to have the filler capable of again melting or softening and shifting position in the shoe under the influence of low heat. In my foundation Patent 30 No. 832,002 of September 25, 1906, and my Patent No. 861,555 of July 30, 1907 (which is ancillary to the earlier patent) I have specified and claimed a non-oxidizing, 35 permanently plastic, quick-setting mass, composed of comminuted cork, each granule of which is coated with a permanently sticky binder containing a waxy material, such for instance as resinous residuum of petroleum or wax tailings. This mass makes a good 40 filler under ordinary conditions of use, but I find that if shoes containing this filler are subjected to prolonged exposure to undue heat, as by standing them over a hot radiator, the filler may soften and shift under the pressure of the foot, and accordingly 45 one of the main objects of my present invention is to provide a compound which, when it has once been put in place and caused to set, will not soften or respond 50 readily to such outside heat but will remain tough, and yet will retain substantially all of the leading advantages which have made my previous shoe fillers and cementitious 55 compounds valuable and acceptable. I have found that if the permanently sticky mass above referred to be stiffened by a little paste, preferably aqueous, its character, while still retaining its elastic and water- 60 proof qualities, is much improved in that it will stand any heat within the limit of the ordinary resisting capacity of leather, without becoming either mushy or crumbly. The cementitious binding agent as described in

the patents referred to is of a gummy nature, readily influenced by heat, and I still use the same binding materials, and the same granular portions of cork or other equivalent comminuted material, and the same general treatment of mixing the component parts to produce my present product. The paste I prefer to use is ordinary starch paste, but I may use, instead of starch paste, any of the well-known pasty stiffeners or materials which may be moistened or mixed into a paste becoming when set a firm binding agent not softening under heat, as described, whether of vegetable origin, as dextrin, gluten, or gum arabic, or of animal origin, as glue, casein, albumen, or of mineral origin as the soluble silicates or silicic acid. In fact, I do not wish, at this point, to lay stress on any particular material, as I desire to have my claims cover all substances of the general character indicated. While these pasty ingredients may be introduced into the filler in the form of paste, *i. e.* wet (and cooked, when of a nature requiring cooking in order to become pasty), I wish to mention at this point a further important feature of my invention in its preferred or more complete embodiment. This further important feature of my invention is so to handle the ingredients that the shoe-bottom filler may be supplied in ready-made form to shoe factories and kept until wanted for use, when its quality will be found to be exactly the same as when first manufactured. If the pasty material is inserted in the compound in the form of separately and fully prepared paste, the filler must be used at once or at least soon, because the paste will gradually change the compound and stiffen or set it to a more or less permanently tough condition, not suitable for subsequent application to the shoe-bottom, and accordingly, in order to carry out my last mentioned object above, I preferably do not introduce the pasty ingredient as an already made, separate mixture at the beginning, but introduce the paste-forming ingredient in a more or less dry state at the beginning in such manner and relation to the other ingredients that it is restrained from fulfilling its stiffening or setting function and that the entire compound may be subsequently subjected to a heating or to a moistening or steaming process which will then complete the formation of the pasty portion of the compound and thereby permit the stiffening ingredient to become active and assert its desired and ultimate stiffening influence on the filler, while at the same time permitting the latter to be expeditiously handled for installation within the shoe bottoms. The compound as such, as already stated, is made by introducing into the waxy or gummy components of the shoe-

bottom filler a proportionate amount of flour, starch, dextrin, casein, or other mucilaginous matter or animal, vegetable, or mineral substance, as mentioned, capable of absorbing moisture and being thereby converted into a paste through the moisture from the steam, etc.

To make my invention fully understood, I will describe it with relation to shoe-bottom filler when made by the preferred method as above explained, but it will be understood that this is illustrative only and does not thereby restrict me to this embodiment, or variety of filler, as it is merely the one preferred of many coming within the purview of this patent.

A suitable portion of granulated or finely ground cork is poured into a mixer, together with the gluten or starchy material, such as coarse wheat flour, in a preferably dry state, which is preferably sifted or sprinkled upon the ground cork until each granule of cork is coated as evenly as may be with a layer of the powdered flour. This coated cork is then treated according to the method already described in the patents mentioned, with the waxy or gummy material there described which is atmospherically resistant, (*i. e.* remains unaltered or unaffected by exposure to the air, for all practical purposes of the filler) and thoroughly mixed therewith. The sticky binding agents, such as resinous residuum of petroleum or wax tailings, or a mixture of gutta-percha, resin and paraffin oil (or the other gums, pitches, resins, or distillates of my before mentioned patents) are slowly introduced in a low-heated condition until each gluten-covered cork granule is also enveloped with an exceedingly thin coating of the pitchy material. This forms the filler, as such, for the market, capable of being kept thus until used. Afterward, in use, the mixture is subjected to live steam until the starch is converted into paste, more or less disseminated through the mass. The flour (still using the same paste-forming or stiffener ingredient by way of illustration) and resinous waxy ingredients, after becoming intimately mixed, allow of this further admixture therewith of water in a manner not possible without the presence of the flour (*i. e.* of the paste-making component—whichever one or ones may be used), and it is my belief that this admixture of water separates or subdivides the free particles of the sticky ingredients into minute parts which are enveloped with the glutinous or starchy or other stiff setting mass as mentioned in such a manner that, when the compound sets, these minute parts become a part of the paste, and are held thereby in subjection, and while serving to give extreme stickiness and binding efficiency to

the mass, the set paste prevents the latter from readily becoming soft again, and unites with the wax or gum sufficiently to produce a toughness somewhat like leather, giving strength and resisting qualities. The moisture-swelled or jellified pastes, or at least the moisture-laden or absorbing powders of the stiffener, help to keep separate minute parts of the sticky, gummy, or tarry component, thereby rendering the adhesive or sticky principle of the latter inactive, but as soon as the water has evaporated from the paste or stiffener the latter can no longer repel the particles of said sticky component within the filler body, and hence a union takes place which is of great value in effecting the results sought. The sticky component then penetrates or permeates or sweats through the entire mass, bringing to the front the waterproof principle, but without destroying the stiffening binder, which thereafter maintains the filler in a substantially non-shifting responsiveness to ordinary conditions of heat. The flour or other pasty ingredients also act, to some extent, as a stop or varnish to prevent the wax from penetrating the cork. Cork has naturally a certain proportion of resin, and as the wax tailings, gutta, and other ingredients of my composition have an affinity for this resin, there is a tendency for these materials to follow the resin into the pores of the granules, which tendency is hindered to some extent by the starchy paste or other coating, especially when the filler is made in the manner just described by way of illustration. This preserves to a larger degree than heretofore the natural resiliency of the cork, since the latter, when charged with the wax tailings, etc., tends to become a little sluggish and to recover somewhat slowly from pressure or distortion. I have indicated but one way of getting my paste into the composition. Obviously when flour is used, heat and moisture are necessary to convert it into paste. The moisture may be supplied as indicated above by steam direct. The granules of cork may be slightly moistened with water or other liquid before the flour is applied to retain more of the flour-coating, if desired. If other pastes or stiffening agents are used, their appropriate solvents must of course be employed. If the hardening or softening or setting of the paste is to be accomplished by any chemical means, such means should be introduced at the proper time, with the petroleum residuum, gutta percha, etc., or later. Thus if gelatin be used, potassium bichromate may be added to the waxy component; if casein, an alkaline substance, such as lime or borax, may be added. Some of these, as for example casein when an alkaline substance is used as aforesaid, produce an extremely

sticky paste which therefore becomes in itself a strong binder and does not require such a great stickiness in the gummy or pitchy component. The casein, for instance, 5 or for that matter starch, after being turned into a paste is naturally brittle when set, but by employing suitable chemical means, as stated, this normally brittle component is combusted and expanded or swelled and 10 thickened and at the same time becomes much more sticky, so that the waxy or gummy component need not be relied upon primarily for this purpose but only to supplement the now sticky pasty component, 15 so far as the requirements of the filler or of the particular kind of pasty component make necessary for further softening and waterproofing purposes. The granular or powdery casein, for instance, or starch, and 20 the powdery alkaline substance are mixed with the cork and other components, and then, when subjected to heat and moisture, effect a chemical change into the desired mucilaginous, cohesive condition.

25 Instead of materials which are merely potential pastes, of the character of those indicated above, whose qualities as pastes are developed by further treatment, either physical or chemical, I may use upon the 30 cork granules pastes which are actually such already. Thus, starch paste already liquid, or dextrin in solution, may be mixed with or spread upon such granules before the waxy component is applied.

35 The proportionate amount of gluten or other paste-forming material used varies according to the nature or formation of the waxy constituents and granulated parts. I 40 furnish herewith several formulae which I have found useful: granulated cork 6 parts by weight, coarse flour 4 parts by weight, gummy binding material 11 parts by weight; or, granulated cork 8 parts by weight, dextrin 4 parts by weight, gummy binding material 14 parts by weight.

45 My material may be made in the factory where it is to be used, or it may be prepared ready to be mixed in said factory with the ground cork, but I prefer to prepare and 50 ship it all prepared ready for use or application, when heated slightly, to the shoe bottom. For this reason, I prefer, and indeed consider as a chief feature of the more complete embodiment of my invention, the 55 making of the compound as first described, *i. e.* mixing together the flour (for example) and cork dry and then mixing in the gummy or pitchy component. This gives the mass sufficient cohesion to allow it to be packaged 60 properly for shipment, and yet it holds the paste-forming ingredients inactive until it is desired to use the filler. On the other hand, the flour or powdery ingredient or 65 ingredients deaden the gummy or pitchy component to a sufficient extent to render

the stickiness latent, as it were, or not sufficiently active to bind the mass together with any appreciable tenacity, so that the filler mass is thereby left in a substantially granulated condition, the coated granules of cork 70 being incapable of adhering strongly to each other as is the case in that species of filler which is contained in my Patents Nos. 832,002 and 861,555. In other words, my present invention solves in a practical way 75 (but different from the solution of the problem as contained in said Patent 832,002) the problem of placing the filler before the shoe manufacturers in a form which facilitates 80 its convenient manipulation by the operator who desires to segregate a small mass from the larger bulk. One of the serious problems of my original filler, as first made prior to the invention contained in Patent No. 832,002, was that when the filler mass was 85 put in a large package, as for instance packed in a case or barrel, the particles would cling together with such tenacity that the entire barrelful became an unmanageable mass which could neither be broken 90 apart, because of its great tenacity, nor pried apart without unwarranted effort, nor melted apart on account of the large bulk and slow heat transmission. This problem accordingly is solved by my present invention 95 which, although providing substantially the same ultimate stickiness, maintains said stickiness latent until the filler mass has been transported to the shoe manufacturer 100 and is in the hands of the operator and ready for use. Because of the suppression 105 of the normally active stickiness of the gummy or sticky constituents by means of the incorporation therewith of the flour or powdery constituent, the result is that the filler mass has very little or no cohesion (whether it has any or not depending upon the proportionate amount of the gummy or pitchy component), and hence it becomes 110 perfectly practicable to ship it loose in bags like meal-bags or in any other form of package inasmuch as it can be readily shaken out. In the form in which I prefer to make it, it barely holds together, so that the operator can very readily take up a handful of it 115 from the mass without any substantial resistance being offered by the sticky component and without any tendency of the filler to adhere to his hand. Thus, my invention provides means rendering the filler 120 capable of convenient packaging and subsequent removal from its container and segregation for use without being molded into loaves and coated with cork, or other non-adhesive material, as in my Patent No. 832,002 on the one hand, and without any 125 danger of its sticking into an unmanageable mass on the other hand. When, at any later time, it is desired to apply the filler in 130 the shoe factory, a loaf or quantity of this

mixed mass if made with flour as in the illustrative example is placed in a suitable steaming basin and subjected to a thorough steaming or cooking, which completes the 5 formation of the filler, said steaming or cooking bringing into immediate action the paste-forming ingredients, which are at once turned into actual paste throughout the mass. So likewise, when other stiffening agents are employed with their proper 10 moistening solvents or affinities required for making them into pastes, so that they will set or stiffen, as already explained, the combination is facilitated by heat or otherwise 15 as already set forth. This feature of my invention therefore accomplishes two functions, first, it enables me to restrain or postpone the toughening and thickening of the mass until the shoe is actually filled, and, 20 second, it provides a filler in a sleek condition, *i. e.* steam-charged and moist (in the preferred form, as explained in the illustrative example) and having a comparatively slippery or smooth surface for the knife or 25 tool to slide readily over at the moment the operator is filling the shoe with said filler. My object is to introduce into my previous 30 waxy, gummy or pitchy cementitious filler compound, sufficient pasty, drying matter to make a binder which has characteristics entirely distinct from its principal cementing component in that it has a hardening and toughening capability and is not seriously softened or influenced by low heat, 35 and yet this toughening and hardening element is permanently held in check by the permanent cementitious binding agent, so that the mass cannot become dry or hard and brittle. A further object in the more 40 complete development of my invention, is to cater to the commercial want of an economical, simple article, mixed beforehand to be stored for an indefinite period without developing the dormant mucilaginous or 45 pasty drying or setting, hardening, toughening and stiffening, and heat resisting principle within it, and this object is accomplished by simply introducing the ingredients, leaving their conversion into paste 50 (and hence their hardening and setting) until the moment of use, when the compound, without requiring any further mixing or stirring, is subjected to the action of hot water or other suitable agent for forming the stiffening and toughening component 55 which permeates every part of the mass. I prefer steam-vapor, which does not necessarily show any water present, the moisture being absorbed by the gluten or other stiffening, heat resisting component, which then 60 never becomes in the true sense a paste, the enveloping waxy compound which coats each particle of gluten holding the latter in check, merely allowing each minute particle 65 or grain of the flour or starch (for example) to swell and become at once active in producing its drying and toughening functions but not sufficiently controlling to cause slow-setting, as might be expected of that form of paste. On the contrary, when once installed 70 in a shoe, it sets at once so that the shoe can pass on almost immediately to the next step in its manufacture. The hardening and toughening of the mass is due to the evaporation from the gluten (for example) 75 of the moisture, *i. e.* to its setting, and the waxy components maintain this toughness, while still retaining and maintaining the permanent pliability, elasticity, etc., substantially permanent and unchanged for an 80 indefinite period extending beyond the natural life of the shoe.

I do not restrict my invention to requiring the filler to be applied hot, as the same ingredients as above set forth, may be used cold, simply by providing the completed mixture as a moist dough, kept in a closed barrel until wanted. Also, the above principal objects may be accomplished by providing the filler in a very wet, pasty condition and bringing about the quick setting by chemical action at the time of installing the layer of filler in the shoe, for instance when casein, other proteids or glutinous or 90 mucilaginous substances are used for the heat-resisting properties of the filler, the quick-setting or jellifying may be secured by adding a suitable chemical, preferably a powder, as, in the case of proteids, lime (producing caseinates of lime, etc.), preferably by sifting or mixing in the lime just as the filler is about to be installed. Also 95 gelatinous matter alone admixed with my patented filler material will accomplish practical results. In the claims I use the expression "pasty component" broadly to include all the stiffening and drying or heat-resisting ingredients mentioned *i. e.* the ingredients herein mentioned for admixture 100 with the previous cementitious components (of the filler as set forth in my patents aforesaid) to produce the new results of my present invention. All of these compounds have also the sleeking capacity, first mentioned, whereby the applying tool slips or 105 smoothes over the layer unaided without undue dragging or clinging.

The various species herein covered generically, but not claimed herein specifically, 110 form the subjects matter of divisional applications.

Having described my invention, what I claim and desire to secure by Letters Patent of the United States is:—

1. The herein described article, consisting of an atmospherically resistant, permanently pliable and cohesive mass, heat-resistant under practicable conditions of 125 temperature in use when fully set, substantially as set forth.

2. The combination with a shoe-bottom 5
filler having a body of comminuted filler-
material united by a sticky, gummy binder,
with a tendency to flux under heat, of set-
ting means for overcoming said tendency
under practicable conditions of tempera-
ture in use, substantially as set forth.
3. The herein described article, consist-
ing of a permanently pliable, adhesive
10 mass, quick setting, having a leather-like
toughness when set and heat-resistant un-
der practicable conditions of temperature
in use when fully set, substantially as set
forth.
4. The herein described article, consist-
ing of a permanently pliable, adhesive
15 mass, quick setting, having a leather-like
toughness when set, sleek under the smoothing
iron, and heat-resistant under practi-
cable conditions of temperature in use when
fully set, substantially as set forth.
5. The herein described article, consist-
ing of a base of filler material, united with
20 a permanently pliable, cohesive and ad-
hesive binder, containing a stiffening com-
ponent held normally inactive, but capable
of asserting itself in the process of appli-
cation, substantially as set forth.
6. The herein described article, consist-
ing of a base of filler material, united with
25 a permanently pliable, cohesive and ad-
hesive binder, containing a stiffening and
toughening component held normally in-
active, but capable of asserting itself in the
process of application, substantially as set
forth.
7. The herein described article, consist-
ing of a base of filler material, united with
30 a permanently pliable, cohesive and ad-
hesive binder, containing a stiffening heat-
resistant and toughening component held
normally inactive, but capable of asserting
itself in the process of application, substan-
tially as set forth.
8. A permanently elastic quick setting
35 binder consisting of a gummy base and a
restraining agent of a pasty nature, the
proportions being such that the compound
is firm under practicable conditions of
temperature in use and elastic, substantially
as set forth.
9. The combination with comminuted
40 shoe filler material of a permanently elastic
quick setting binder consisting of a sticky
waxy base and a restraining agent of a
pasty nature, the proportions being such
that the filler is firm under practicable
conditions of temperature in use and elastic,
substantially as set forth.
10. The combination with comminuted
45 shoe filler material, of a permanently elastic
quick setting binder consisting of a sticky
waxy base and a restraining agent of a
pasty nature, the proportions being such
that the filler is firm under practicable con-
ditions of temperature in use, yielding, and
sleek under a smoothing iron when applied
to a shoe, substantially as set forth.
11. A shoe-bottom filler, comprising filler-
body material admixed with a compound
50 consisting of a paste mixed with a softening
means, in proportion sufficient to change
the otherwise hard-setting nature of the
paste to a permanently pliable, tenacious
binder for said body material, substantially
as set forth.
12. The combination with a shoe-bottom
filler having a body of comminuted filler-
material united by a binder comprising a
component having a normal tendency to
harden and become brittle when set, and a
modifying component imparting permanent
55 pliability and cohesiveness to the mass, sub-
stantially as set forth.
13. The combination with a shoe-bottom
filler having a body of comminuted filler-
material united by a binder comprising a
component having a normal tendency to
harden and become brittle when set, and a
modifying component imparting perma-
60 nent pliability and cohesiveness to the mass,
one of said components having a sticky
property rendering the mass adhesive, sub-
stantially as set forth.
14. The combination with a shoe-bottom
filler having a body of comminuted filler-
material united by a binder comprising a
component having a normal tendency to
harden and become brittle when set, and a
modifying component imparting perma-
65 nent pliability and cohesiveness to the mass,
both of said components having a sticky
property rendering the mass adhesive, sub-
stantially as set forth.
15. The combination with a shoe-bottom
filler having a body of comminuted filler-
material united by a binder comprising a
component having a normal tendency to
harden and become brittle when set, and a
softening component, each of said com-
70 ponents influencing the other to render the
mass permanently pliable and cohesive and
heat-resistant under practicable conditions
of temperature in use when fully set, sub-
stantially as set forth.
16. The combination with a shoe-bottom
filler having a body of comminuted filler-ma-
terial united by a binder comprising a sticky
75 mucilaginous component, having a normal
tendency to harden and become brittle when
set, and a softening, heat-fluxing water-
proofing component acting to modify said
normal hardening tendency of said other
component, rendering the filler mass per-
80 manently pliable and cohesive, substantially as
set forth.
17. A permanently elastic quick setting
85 binder consisting of wax tailings and a
modifier or restrainer, the proportions being
such that the compound is firm under prac-
90

- ticable conditions of temperature in use and elastic, substantially as set forth.
18. The combination with comminuted 5 filler material, of a permanently elastic quick setting binder consisting of wax tailings and a modifier or restrainer, the proportions being such that the filler is firm under practicable conditions of temperature in use and elastic, substantially as set forth.
19. The combination with comminuted 10 filler material, of a permanently elastic quick setting binder consisting of wax tailings and a modifier or restrainer, the proportions being such that the filler is firm under practicable conditions of temperature in use, yielding, and sleek under the smoothing iron, substantially as set forth.
20. A binder for shoe filling material containing a base which is substantially wax tailings and a paste substantially as described. 15
21. A binder for shoe filling material consisting of wax tailings and starch paste.
22. The herein described article, consisting of a non-volatile, permanently-adhesive 20 and binding body, containing a paste-forming component, low-melting, and waterproof when applied in use, substantially as set forth.
23. The herein described article, consisting of a non-oxidizing, permanently-sticky 25 base, combined with an elastic gum, and paste-producing component, and adhesive when cold, substantially as set forth.
24. The herein described article, consisting of a non-oxidizing, permanently-tacky 30 base, combined with an elastic gum, and a hardening and toughening agent of a pasty nature, substantially as set forth.
25. The herein described filler, comprising 35 filler-body-material admixed with a compound consisting of a soft, sticky gum, and a hardening and toughening agent of a pasty nature, substantially as set forth.
26. A shoe-bottom filler, consisting of a 40 base united with a binder into a permanently-tenacious, quick-setting, permanently-pliable mass, containing a modifier or restraining agent of a pasty nature, and capable of being melted into a thin pliable 45 layer, filling the shoe-bottom, substantially as set forth.
27. A shoe-bottom filler, comprising filler-body material admixed with a compound 50 consisting of a paste mixed with a softening means, consisting at least in part of wax tailings, in proportion sufficient to change the otherwise hard-setting nature of the paste to a permanently pliable, tenacious binder for said body material, substantially as set forth.
28. A shoe-bottom filler, consisting of a 55 normally substantially unchangeable, permanently-pliable, quick-setting mass, composed of a base, united with a permanently 60
- sticky component, and a restraining agent capable of rendering the filler, when applied, heat-resistant at practicable temperatures of use, substantially as set forth.
29. A shoe-bottom filler, consisting of a 65 normally substantially unchangeable, permanently-pliable, quick-setting mass, composed of a base, united with a permanently-sticky component, and a restraining agent capable of rendering the filler, while being 70 applied, sleek, and thereafter heat-resistant at practicable temperatures of use, substantially as set forth.
30. A shoe-bottom filler, consisting of a 75 base united with a binder into a permanently-tenacious, quick-setting, permanently-pliable mass, containing a modifier or restraining agent of a pasty nature capable of rendering the filler, when applied, heat-resistant at practicable temperatures of use, and of being molded into a thin pliable 80 layer filling the shoe-bottom, substantially as set forth.
31. A shoe-bottom filler, consisting of a 85 normally substantially unchangeable, permanently-pliable, quick-setting mass, composed of a base, united with a permanently-sticky component having a low melting-point, and a stiffening, toughening, restraining agent capable of rendering the filler, when applied, heat-resistant at practicable 90 temperatures of use, substantially as set forth.
32. A shoe-bottom filler, consisting of a 95 normally substantially unchangeable, permanently-elastic, quick-setting mass, composed of a base, united with a permanently-sticky component having a low melting-point and serving to render said mass waterproof, and a restraining agent capable of rendering the filler, when applied, heat-resistant at practicable temperatures of use, substantially as set forth.
33. A shoe-bottom filler, consisting of a 100 resilient base united with a viscous binder into a permanently-tenacious, quick-setting, permanently-elastic and water-repellent mass, and a pasty component capable of being molded into a thin pliable layer filling the shoe-bottom, substantially as set forth.
34. A shoe bottom-filler, consisting of a 105 normally substantially unchangeable, permanently-elastic mass, composed of finely comminuted filler material having each granule thinly coated with a permanently-tough binder containing a pasty component, substantially as set forth.
35. A shoe-bottom filler, consisting of a 110 filler-body in a fragmentary condition, thoroughly mixed with a binder into a permanently-tenacious, permanently-elastic and moldable mass and containing a restraining agent normally inactive, but capable of being made active, upon applying the filler, so as to render the filler in the shoe-bottom 115

non-shiftable and heat-resistant at practicable temperatures of use, substantially as set forth.

36. A shoe-bottom filler, consisting of a 5 filler-body in a fragmentary condition, thoroughly mixed with a binder into a permanently-tenacious, quick-setting, permanently-elastic and moldable mass and containing a restraining agent normally inactive, but capable of being made active, upon 10 applying the filler, so as to render the filler in the shoe-bottom non-shiftable and heat-resistant at practicable temperatures of use, substantially as set forth.
37. A shoe-bottom filler, consisting of a 15 filler-body in a fragmentary condition, thoroughly mixed with a binder into a permanently-tenacious, sleek under the smoothing iron, permanently-elastic and moldable 20 mass and containing a restraining agent normally inactive, but capable of being made active, upon applying the filler, so as to render the filler in the shoe-bottom non-shiftable and heat-resistant at practicable 25 temperatures of use, substantially as set forth.

38. A shoe-bottom filler, consisting of a 30 filler-body in a fragmentary condition, thoroughly mixed with a binder into a permanently-tenacious, permanently-elastic and moldable mass and containing a restraining agent normally inactive, but capable of being made active, upon applying the 35 filler, so as to render the filler in the shoe-bottom non-shiftable tough and heat-resistant at practicable temperatures of use, substantially as set forth.

39. A shoe-bottom filler, consisting of 40 comminuted filler material mixed with a permanently-flexible, viscous-binder, in a 45 permanently-elastic mass of a consistency suitable for application in the cavity between the innersole and outer sole of a shoe, said mass having a low melting-point, and 50 containing a restraining agent, normally inactive, but capable of being made active, upon applying the filler, so as to render the filler in the shoe-bottom heat-resistant under practicable temperatures of use, substantially as set forth.

40. A shoe-bottom filler, consisting of 55 comminuted filler material held together by a permanently-flexible, viscous-binder, in a permanently-elastic, quick-setting mass of a 60 consistency suitable for application in the cavity between the innersole and outer sole of a shoe, said mass having a low melting-point and being compressible and resilient when cold, and containing a restraining 65 agent, normally inactive, but capable of being made active, upon applying the filler, so as to render the filler in the shoe-bottom heat-resistant under practicable temperatures of use, substantially as set forth.

41. A shoe-bottom filler, consisting of

comminuted filler material held together by a permanently-flexible, viscous-binder, in a permanently-elastic, sleek under the smoothing iron mass of a consistency suitable for application in the cavity between the inner- 70 sole and outer sole of a shoe, said mass having a low melting-point and being compressible and resilient when cold, and containing a restraining agent, normally inactive, but capable of being made active, upon applying the filler, so as to render the filler in the shoe-bottom heat-resistant under practicable temperatures of use, substantially as set forth.

42. A shoe-bottom filler, consisting of 80 comminuted filler material held together by a permanently-flexible, viscous-binder, in a permanently-elastic mass of a consistency suitable for application in the cavity between the innersole and outer sole of a shoe, 85 said mass having a low melting-point and being compressible and resilient when cold, and containing a restraining agent, normally inactive, but capable of being made active, upon applying the filler, so as to 90 render the filler in the shoe-bottom tough and heat-resistant under practicable temperatures of use, substantially as set forth.

43. A shoe-bottom filler, consisting of a 95 normally substantially unchangeable, permanently-elastic, quick-setting mass of finely comminuted cork tenaciously held together by a binder whose controlling ingredient is resinous residuum of petroleum, modified by an ingredient of a pasty nature and having a hardening influence, substantially as set forth.

44. A shoe-bottom filler, consisting of a 100 low melting, non-oxidizing, permanently-elastic, quick-setting mass containing resinous residuum of petroleum modified by a stiffening paste, substantially as set forth.

45. A shoe-bottom filler, consisting of a 105 normally substantially unchangeable, permanently-elastic, quick-setting, non-inflammable, water-repellent mass pliable and tenacious as described, yet stiff in the shoe to prevent shifting or bunching in use, and containing sticky residuum of petroleum modified by a starchy paste, substantially as 110 set forth.

46. A shoe-bottom filler, consisting of 115 granular cork and filler-binder united together in a granular form for the market, having each granule of cork enveloped by 120 the binder in a state maintaining the filler mass in a granular condition with the binding qualities maintained latent but capable of development for use.

47. A shoe-bottom filler, consisting of 125 comminuted filler material having each grain separately enveloped with a coating of normally sticky adhesive material, combined with neutralizing means for rendering the stickiness inactive, in such proportion 130

tions that the filler mass is substantially without cohesion and its granular condition is substantially preserved for quick handling and segregating in use by the shoe operative.

5 48. The herein described filler, comprising a granular substance having a coating of normally stiff glutinous material, and an adhesive binder restrained from said granular substance by said coating, substantially as set forth.

10 49. The method of modifying a cementitious compound, which consists in uniting with it, an agent of a stiffening character 15 and of a paste-forming nature, in such proportion that the temperature range of permanent-elasticity of the compound is extended to the limits of practicable conditions of use, substantially as set forth.

20 50. The method of making a shoe filler, which consists in uniting with the granular filler mass, a sticky mucilaginous component having a normal tendency to harden and become brittle when set, and a softening, heat-fluxing, waterproofing component in proportion to modify said normal hardening tendency of said other component so as to render the filler mass permanently pliable and cohesive, substantially as set forth.

25 51. The method of modifying a cementitious pliable compound, which consists in uniting with it, an agent of a stiffening character and of a paste-forming nature, said agent being introduced in an inactive 30 state and thus maintained until the compound is to be used, and then rendering said agent active by introducing moisture thereto, said agent being in such proportion that when rendering active, it renders the compound heat-resistant to the extent of remaining firm under practicable conditions 35 of temperature in use without becoming fragile and rigid, substantially as set forth.

40 52. The method of modifying a waxy binder for shoe-filling material, which consists in uniting with it, an agent of a stiffening character, and of a pasty nature, in such proportion that the temperature range of permanent elasticity of the binder is extended to the limits of practicable conditions 45 of use of the shoe, substantially as set forth.

55 53. The method of making an elastic, quick-setting binder for shoe-filling material consisting in adding to a base of a pitchy nature, a restraining or stiffening agent of a pasty nature in such proportions that when the filling material is added to the binder, the resulting filler is firm under 60 practicable conditions of temperature in use, and elastic, substantially as set forth.

65 54. The method of making an elastic, quick-setting binder for shoe-filling material consisting in adding to a base of a pitchy nature, a restraining or stiffening

agent of a pasty nature in such proportions that when the filling material is added to the binder, the resulting filler is firm under practicable conditions of temperature in use, elastic, and sleek under the smoothing iron, 70 substantially as set forth.

55. The method of making an elastic, quick-setting binder for shoe-filling material consisting in adding to a base of a pitchy nature such as wax tailings, a restraining or stiffening agent of a pasty nature in such proportions that when the filling material is added to the binder, the resulting filler is firm under practicable conditions of temperature in use, and elastic, 75 substantially as set forth.

56. The method of making a permanently-elastic, quick-setting binder for shoe-filling material consisting in adding to a sticky or tacky base, such a proportion of restrainer 80 of a pasty nature that when filling material and the binder are mixed and ready for application to a shoe, the resulting shoe-filling material is firm under practicable conditions of temperature in use, elastic and sleek 85 under the smoothing iron, substantially as set forth.

57. The method of modifying a binder for shoe-filling material, the base of which is substantially wax tailings which consists in 90 adding such a proportion of a toughening and stiffening agent of a pasty nature, that the tacky or sticky nature of the tailings is subdued to such an extent that the filler is sleek when the smoothing knife is applied 95 to it, substantially as set forth.

58. The method of making a shoe filler, which consists in thoroughly intermingling comminuted filler material, a potential comminuted stiffening agent, and a sticky 100 binder until each granule of the filler material is coated with said ingredients, and thereafter supplying means to develop the stiffening qualities of said stiffening agent, substantially as set forth.

110 59. The method of making a shoe filler, which consists in thoroughly intermingling comminuted filler material, a potential comminuted stiffening agent, a potential comminuted chemical agent capable of subsequently dissolving and swelling said stiffening agent into a pasty condition, and a softening component until each granule of the filler material is coated with said ingredients, and thereafter supplying developing means to bring about the mucilaginous union of all of said ingredients, substantially as set forth.

115 60. The method of making a shoe-bottom filler, which consists in coating granules of comminuted filler material with a stiffening-forming agent primarily, and in then mixing said granules so coated with a permanently-sticky binder, substantially as set forth.

61. The method of making a shoe-bottom 5
filler, which consists in enveloping granules
of comminuted filler material with a stiffening
agent in an inactive state, then mixing
said granules so enveloped with a
permanently-sticky binder, and finally introducing
a quickening ingredient for developing
in the compound the stiffening effect
of said agent, substantially as set forth.
- 10 62. The method of making a shoe-bottom
filler, which consists in coating granules of
comminuted filler material with a stiffening
agent in a powdered state, then mixing said
granules so coated with a sticky binder, and
subsequently adding a moistener for the
stiffening agent, substantially as set forth.
- 15 63. The method of making a shoe-bottom
filler, which consists in coating granules of
comminuted filler material with a potential
20 stiffening agent, then mixing said coated
granules with a sticky binder, and supplying
means to develop the stiffening qualities
of said stiffening agent, substantially as set
forth.
- 25 64. The method of making a shoe-bottom

filler, which consists in coating granules of
comminuted filler material, such as cork,
with a starchy powder, such as wheat flour,
then mixing said coated granules with a
permanently-sticky and elastic binder, and
finally subjecting the mixture to the action
of steam whereby the starchy powder is converted
into a paste, substantially as set forth. 30

65. The method of making a shoe-bottom
filler, which consists in sprinkling upon
granules of cork dry flour, stirring the granules
to distribute the flour evenly thereon,
mixing the granules so treated with a sticky
binder containing wax tailings, and subjecting
this mixture to the action of steam 40
whereby the starch becomes converted into
a paste distributed evenly throughout the
binder, substantially as set forth.

In testimony whereof, I have signed my
name to this specification, in the presence of 45
two subscribing witnesses.

ANDREW THOMA.
